UNITED STATES PATENT OFFICE.

GEORGE W. DONNING, OF EAST ORANGE, NEW JERSEY, ASSIGNOR TO HARRY T. AMBROSE, OF ORANGE, NEW JERSEY.

TYPE-WRITER.

1,126,420.

Specification of Letters Patent.

Patented Jan. 26, 1915.

Original application filed June 21, 1901, Serial No. 65,468. Divided and this application filed September 21, 1903. Serial No. 174,065.

To all whom it may concern:

Be it known that I, GEORGE W. DONNING, a citizen of the United States, residing at East Orange, in the county of Essex and State of New Jersey, have invented certain new and useful Improvements in Type-Writers; and I do hereby declare the following to be a full, clear, and exact description of the invention, such as will enable others skilled in the art to which it appertains to make and use the same.

My invention relates to an improved type-bar carrying a multiple-type head for typewriting machines, and so constructed as to be compact and durable in construction and certain in operation.

The invention is fully disclosed in United States Patent No. 745,163, issued November 24th, 1903; the present application constituting a true division of the application upon which that was granted.

My invention resides in a construction in which interference or impact between descending and ascending type-heads will cause the ascending type-head to shift sufficiently to prevent interlocking and jamming of such interfering type-heads, while the descending type-head will be positively blocked against being shifted thereby in a direction opposite to descent of the bar.

My invention consists in the constructions, combinations, and arrangements herein described and claimed.

In the accompanying drawings, forming a part of this application and in which similar reference symbols indicate corresponding parts in the several views: Figure 1 is a sectional elevation of a typewriting machine, with parts omitted for clearness, illustrating my invention applied thereto; and Fig. 2 is a detail elevation on a larger scale, showing my improved multiple-type-bar.

Referring to the drawings, in which I have illustrated a flat-platen, or book, typewriter, *a* indicates a type-bar of any desired shape, pivotally carrying a multiple type-head *a*¹, shown as provided with three type, *t*, *t*¹, and *t*². The type-head is provided with an extension or lug *a*², which is connected by a link *a*³ with an actuating lever *a*⁵. The lever *a*⁵ is pivotally supported on the type-bar, and is provided with a tail piece *a*⁶ constructed to engage a shiftable

member *b* upon movement of the type-bar. 55 Teeth or projections *a*⁷ are formed on the lever *a*⁵ and with these engages a spring element or pawl *a*⁸ carried by the type-bar and provided with an arm *a*⁹ arranged to engage a type-head releaser *a*¹⁰ when the type-bar is in its upward, normal position. If desired, the arm *a*⁹ may constitute a loop embracing the type-bar. A spring *a*², carried by the type-bar, is connected to the lever *a*⁵ and acts to return the type-head to 60 its normal position when the spring pawl *a*⁸ is disengaged from the teeth *a*⁷. The lower end of the type-bar is pivoted at *a*¹² in a guide-yoke *c*, shown secured to a base plate *d* by a screw *e*. This guide-yoke is 65 preferable to the usual pivot or cone-bearing support, in that it provides a broad guiding surface for the type-bar throughout the latter's entire arc of movement, thus preventing lateral play of the type-bar with 70 slight friction.

A link *f* is shown connecting a toe *a*¹¹ on the type-bar with the inner arm of a key-lever *g*, which latter is pivotally supported at *h* and is provided with a finger-piece *i*. 80 Suitable means, such as a turn-buckle *f*¹, may be provided for adjusting the length of the link *f*. A spring *g*² is shown connecting the inner end of the key-lever and the type-head releaser, for returning the key-lever to its normal position. 85

The means for operating the actuating lever *a*⁵ preferably comprise a segmental bar *b* carried by hangers or rods *l*, which latter are guided in openings formed in the base plate *d* and type-head releaser *a*¹⁰, or in any other convenient portion of the typewriter frame.

A shaft *m*, extending transversely of the typewriter, carries adjacent each end a bell-crank *m*¹, which is pivotally connected at *m*² to one of the hangers *l*. Each bell-crank *m*¹ is preferably connected by a link *n* to an arm *o* secured on a second transverse shaft *o*¹; this second shaft carrying a crank *o*², which is pivotally connected at *o*³ to one of the hangers *l*. An arm *p* is secured to the shaft *m*, preferably near one end thereof, and pivotally supports two slotted links *p*¹ and *p*². A shift-key-lever *r*¹ (for capital letters) carries a pin *r*² extending into the slot of the link *p*¹; and a second shift-key-lever *s* (for numerals and sym-

bols) carries a pin r^4 extending into the slot of the link p^2 ; the pin s^1 swinging on a larger radius than the pin r^4 , as clearly shown in Fig. 1.

5 It will be understood that, upon actuation of the cap-key-lever r , the operating bar b will be raised from its normal position—that shown in Fig. 1—to its intermediate position; and that, upon actuation of the numeral-key-lever s , the bar b will be raised to its highest position. It will further be clear that, upon actuation of the cap-key-lever, the pin s^1 of the numeral-key-lever will slide in its engaging slot, and vice versa, 10 so that actuation of either of said shift-levers will in no manner affect the other. Upon release of either of the shift-levers, the operating bar b and its attached parts may be returned to their normal, lowest position by gravity, or by a spring. When it is desired to print a lower-case character, the key-lever g is actuated and this operation swings the type-bar downward and brings the lower-case type t into printing contact 15 with the paper. The bar b , being in its normal or lowest position, will not engage the tail-piece a^6 to shift the type-head. When, however, an upper-case character is to be printed, the cap-lever r is actuated to 20 shift the bar b to its intermediate position. The key-lever g is then actuated to swing the type-bar downward, whereupon the tail-piece a^6 will engage the bar b and shift the type-head sufficiently to bring the upper-case type t^1 into printing position. The 25 spring pawl a^8 , by engaging the teeth a^7 , positively blocks the type-head, when in any of its adjusted positions, against turning in the directions of the hands of a watch, as shown in Fig. 2. As will be seen, the teeth a^7 are so formed and disposed in relation to the engaging end of the pawl that the latter will effectually bear against said teeth and block the head against any tendency to 30 shift toward normal position. Upon release of the key-lever g , the type-bar returns to its normal, upright position, and the arm a^9 contacts with the type-head releaser a^{10} and forces the spring pawl a^8 from 35 engagement with the teeth a^7 , thus permitting the spring a^2 to swing the type-head into its normal position. Should the bar b be in one or another of its raised positions during such return of the type-bar, the 40 tail-piece a^6 will readily ride over the inclined face thereof, which tends slightly to raise the head-shifting device, comprising the lever a^5 and the link a^4 . The bar b , therefore, may be engaged by the tail-piece 45 a^6 twice during its travel to and from the printing-point, and during each of such engagements serves to actuate the head-shifting device. The shifting of the device during the upward travel of the type-bar is 50 sufficient to permit the type-bar to return 55 to its normal position; otherwise, if the tail-piece engaged the bar b without a yielding movement, the type-bar would be prevented from resuming its proper, normal position and it would, thus, possibly be in the path of descending bars. Besides, it could not 60 become properly positioned to allow the arm of the spring-pawl a^8 to strike the head releaser a^{10} and release the head and permit it to return to its normal position. It will be 65 observed that, by reason of the fact that the trip b is arranged in relatively close proximity to the lever s and also is juxtaposed to the fulcrum of the type-bar, considerably less power will be required to actuate the key-lever when the type-head has to be shifted than if said trip were otherwise disposed. As a result, a comparatively light spring 70 (g^2) for restoring the key-lever to normal position may be employed. By this arrangement and construction, a light, smooth and easy action of the parts is obtained. If a numeral is to be printed, the numeral-shift-key s is actuated to shift the bar b to its highest position, whereupon, during 75 the downward swing of the type-bar, the tail piece a^6 will engage the bar b and adjust the type-head to bring the numeral-type t^2 into printing position; the pawl a^8 positively blocking the type-head in its adjusted position, as previously described.

80 By the expression "blocking", I mean to convey the meaning that the spring-pawl a^8 , subserving the function of a blocking member, holds, blocks and rigidly retains the 85 head against rotation in one direction, that is, in a direction opposite to the descent of the bar, and thus operates for an important purpose: It prevents undesirable shifting of the head to a different printing position, 90 when, for instance, it is in its second or intermediate shifted position, or is in its third or final shifted position. In this connection, I provide a separate and distinct element to 95 effect the blocking, namely, the pawl a^8 , 100 which engages the teeth a^7 in the lever a^5 . Such a construction is to be distinguished 105 from the provision of mere banking or abutting-faces, so-called, on the periphery of a type-head and the sides of the type-bar, 110 which serve merely to prevent excessive and complete rotation of the head in either direction; and, also, from a yielding detent which merely serves to hold the head against 115 unrestrained rotation, as by centrifugal force. In the case of the so-called banking faces, there is no blocking of the head in the sense in which I employ the term because, in my device, the blocking practically occurs 120 simultaneously with the shifting of the head, that is, immediately upon the completion of the shifting or adjustment of the head to one of its shifted positions.

125 The head is actuated or shifted, as already described, when the tail-piece a^6 of the lever 130

a^3 engages the bar b and moves the link a^4 which is connected to the head, and this head-shifting-device and the head are blocked against movement in one direction. 5 The blocking-member a^8 and the lever a^5 also constitute a combined head-shifting and blocking mechanism which possesses the desirable characteristic of being positive in operation and safeguards against undesirable actuation of the head into the wrong printing position in the event the head of a descending bar impinges against any object during its travel to the printing-point.

While I have illustrated my invention applied to a type-head provided with three type, it is obvious that a greater or less number could be employed, if desired.

Having thus fully described my invention, what I claim as new, and desire to secure by Letters Patent is:

1. In a typewriter, a type-bar provided with a type-carrying head shiftable to a plurality of printing positions, a movable device carried by the bar for blocking the head against movement in one direction, and independent means carried by the bar and constantly exerting a force to hold the head under action of the blocking device.
2. In a typewriter, a type-bar having a movable head adapted to be actuated completely and simultaneously blocked against movement in one direction in a predetermined position toward the outset of its downward stroke, and a blocking member carried by the bar, combined with means constructed to shift the head, and a single means for disengaging the blocking member and for maintaining the head normally free while the type-bar is in its upright, normal position.
3. In a typewriter, a type-bar carrying a movable head constructed to be actuated to-

ward the commencement of its arc of movement and simultaneously blocked against movement in one direction, in combination with means carried by the type-bar for effecting actuation and blocking of the head, means independent of the head-actuating means for effecting a release of the same from the blocking means, and means for restoring the type-head to normal position.

4. In a typewriter, the combination with a type-bar carrying a movable head, of a rocking-arm pivoted centrally of the type-bar, a link depending from the type-head and connecting with the rocking-arm, serrations formed on the rocking-arm, and a blocking member disposed on the type-bar and engaging said serrations.

5. In a typewriter, the combination with a type-bar having a head shiftable to a plurality of positions, of a head-shifting device carried by the type-bar for shifting the head, a blocking member carried by the type-bar and constructed to block the head against rotation in one direction in any of its shiftable positions simultaneously with its shifting actuation, and spring-actuating means carried by the type-bar and connecting with the head-shifting device to effect return of the type-head to normal position, and operating-mechanism arranged to engage the head-shifting device to actuate the same into either of its shiftable positions during the travel of the type-bar to the printing point and back to its normal position.

In testimony whereof, I affix my signature, in the presence of two subscribing witnesses.

GEORGE W. DONNING.
